DESIGN FOR A DRESS

Seymour Jacobson, New York, N. Y.

Application August 7, 1940, Serial No. 94,278

Term of patent 3½ years

To all whom it may concern:

Be it known that I, Seymour Jacobson, a citizen of the United States of America, residing in New York city, county of New York, and State of New York, have invented a new, original, and ornamental Design for a Dress, of which the following is a specification, reference being had to the accompanying drawing, forming part thereof, wherein:

I claim:

The ornamental design for a dress, as shown.

SEYMOUR JACOBSON.
